UNITED STATES PATENT OFFICE.

WALTER LANE, OF HOLLAND, MICHIGAN.

PNEUMATIC PIANO PLAYER.

1,422,275.

Specification of Letters Patent. Patented July 11, 1922.

Application filed May 19, 1917. Serial No. 169,669.

To all whom it may concern:

Be it known that I, WALTER LANE, a citizen of the United States, residing at Holland, Michigan, have invented certain new and useful Improvements in Pneumatic Piano Players, of which the following is a specification.

This invention relates to improvements in pneumatic piano players. 10 It has to do with improved web guiding means for controlling the web when the key is varied in transposing. By varying the position of the roll and the web in its relation to the tracker bar such transposing is 15 accomplished.

My invention applies the principles of web guiding exemplified in United States Letters Patent No. 789,053, of May 2, 1905, to J. O'Connor, and similar structures, to 20 a transposing device.

The main object of the invention is to provide an effective transposing device in which the web guiding feature is maintained and in which the loud pedal operating means 25 is also effectively utilized.

Further objects, and objects relating to details and economies of construction and operation will appear from the detailed description to follow.

I accomplish the objects of my invention by the devices and means described in the following specification. The invention is clearly defined in the claims.

A structure constituting a preferred embodiment of my invention is illustrated in the accompanying drawing, forming a part of this specification, in which:

Fig. I is a front view of my transposing mechanism with the music roll shown in 40 position on the tracker bar by dotted lines, showing also the slides that carry the tube to the loud pedal and also the tubes to the web guiding devices.

Fig. II is a front view similar to that of 45 Fig. I, with the music roll shifted to another position in transposing, showing also how slides are shifted in transposing.

Fig. III is an enlarged section of the 50 tracker bar with my improved slide showing the opening for the tube to the loud pedal and also the opening of the tubes to the web guiding devices.

Fig. IV is a sectional view, taken on a line corresponding to line 4—4 of Fig. I, showing how my improved slide in the tracker bar is attached to the transposing mechanism.

Fig. V is a sectional view, taken on a line corresponding to line 5—5 of Fig. II, similar to Fig. IV, with the slides shown in another position, as in said Fig. II.

Fig. VI is a sectional view taken on a line corresponding to line 6—6 of Figs. I and II, showing way for slide and also connections for one of the tubes to the tracker bar transposing device.

Fig. VII is a sectional view taken on a line corresponding to line 7—7 of Figs. I and II, showing means for connecting the tracker bar to the loud pedal tube.

Fig. VIII is a detail elevation view of the 70 connection of the pitman 11 to the rock shaft arm 11'.

In the drawing, similar numerals of reference refer to similar parts throughout the several views, and the sectional views are 75 taken looking in the direction of the little arrows at the ends of the section lines.

Referring to the reference numerals, 1 represents a support for the roll supporting frame 2. The sheet or web supporting rolls 80 3 and 3' are supported by axially adjustable spindles. The roll 3' is supported by the axially adjustable spindles 4' and 7', and the roll 3 is supported by the spindles 4 and 7, the spindles 7 and 7' being driving spindles. 85 The spindle 4 is urged against the roll by the spring 5. The spring 5' urges the spindle 4 normally to the right as shown in the drawing. The spindles 7 and 7' are journaled in frame members 8, the frame members 90 6 and 8 being connected by rods 9 at top and bottom. Details of the means for shifting this spindle carrying frame are not illustrated.

I provide a double pneumatic 12 for actuating the upper roll 3' independently of the shifting of the frame. This double pneumatic 12 is connected by the link 11 to the rock shaft arm 11' on rock shaft 10'. On the opposite end of this rock shaft is a cam 10 100 acting upon the spindle 7 to force it axially against the tension of the spring 5', the spring 5' returning it in the opposite direction when the shifting of the cam permits.

The double pneumatic 12 is controlled from tracker slide or control member 13 and 16 mounted on the inner frame members 6 and 8 in coacting relation to the tracker bar 5 17. The tracker slide or control members have ducts 14 and 18, the ducts being connected to the pneumatic 12 by the tubes 15. The tracker slide or control member 13 is also preferably provided with duct 19 connected to the loud pedal pneumatic. 10

The ducts 14 and 18 operate to do their work by mechanism and means comparable to that shown in the patent to O'Connor, No. 789,053, of May 2, 1905, and therefore do not 15 need to be described in detail here.

With the parts thus arranged, proper transposing is effected. This transposing is effected by shifting the roll on the tracker board either one, two, three or four notes 20 down, or one note up from normal, this being the preferred arrangement and giving a different key.

I have illustrated and described my improvements in one form in which I have 25 embodied the same. I have not attempted to illustrate or describe certain modifications which I contemplate, as I believe the disclosure made will enable those skilled in the art to which my invention relates to embody or adapt the same as conditions may 30 render most desirable.

Having thus described my invention, what I claim as new and desire to secure by Letters Patent, is:

35 1. In a structure of the class described, the combination of a web support, tracker bar, means for controlling the movement of said web support in the direction of the length of the tracker bar comprising pneumatics, and a pair of tracker members slidably associated with said tracker bar and movable with said web support and provided with ducts connected to said pneumatics, one of said tracker members being provided with a 40 loud pedal duct.

2. In a structure of the class described, the combination of a web support, tracker bar, means for controlling the movement of said web support in the direction of the length 50 of the tracker bar comprising a pneumatic, and a member adjustably associated with said tracker bar and movable with said web support and provided with a duct connected to said pneumatic and with a loud pedal duct.

55 3. In a structure of the class described, the combination of a web support, tracker bar means for controlling the movement of said web support in the direction of the length of the 60 tracker bar comprising pneumatics, and a pair of tracker members adjustably associated with said tracker bar and movable with said web support and provided with ducts connected to said pneumatics, one of said tracker

members being provided with an additional 65 duct and connection therefor.

4. In a structure of the class described, the combination of a web support, tracker bar, means for controlling the movement of said web support in the direction of the length 70 of the tracker bar comprising a pneumatic, and a tracker member adjustably associated with said tracker bar and movable with said web support and provided with a duct connected to said pneumatic and with an additional 75 duct and connection therefor.

5. In a structure of the class described, the combination of a tracker bar and a pair of tracker members adjustably associated with said tracker bar and provided with 80 ducts connected to pneumatics, one of said tracker members being provided with an additional duct and connection therefor.

6. In a structure of the class described for use with a transposing device, the combination of a tracker bar, a pair of tracker members slidably associated with said tracker bar and provided with ducts and connections to pneumatics for controlling the web, one of said tracker members being provided with a 85 duct and connection for the loud pedal pneumatic.

7. In a structure of the class described for use with a transposing device, the combination of a tracker bar, a pair of tracker members adjustably associated with said tracker bar and provided with ducts and connections to pneumatics for controlling the web, one of said members being provided with an 90 additional duct and connection.

100 8. In a structure of the class described, the combination of a tracker bar, a tracker member adjustably associated with said tracker bar and provided with a duct and connection to a pneumatic for controlling 105 the web and with an additional duct and connection, for the purpose specified.

9. The combination with the tracker bar of adjustable slides therefor connected by suitable tubes to pneumatic means, and connections for controlling and guiding the rolls and the web.

110 10. The combination with the tracker bar, of adjustable guide bars perforated and connected to pneumatics for guiding the rolls 115 and the web.

11. In a pneumatic player, the combination with the tracker bar, of adjustable pneumatic guide devices, with a duct connection for the loud pedal pneumatic, coacting as 120 specified.

12. In a structure of the class described, the combination of a movable web support, tracker bar, means for controlling the movement of said web support in the direction of the length 125 of said tracker bar comprising pneumatics, and a pair of tracker members slidably associated with said tracker bar

and movable with said web support and provided with ducts connected to said pneumatics, a rock shaft supported on the said frame with a connection to said pneumatics, 5 a cam on the rock shaft disposed to act upon the driving spindle of said pneumatics, and a spring to hold said spindle against the said cam.

In witness whereof, I have hereunto set my hand and seal in the presence of two 10 witnesses.
